GAME OR CHANCE DEVICE

Bert Joseph Simmons, Stillwater, Minn.

Application November 25, 1938, Serial No. 242,373

2 Claims. (Cl. 273--141)

This invention relates to a game or chance device, the primary object of the invention being to provide a device of this character including a governor controlled stopping means for stopping the operating mechanism when the mechanism slows down or reaches a predetermined slow rate of speed.

Another object of the invention is to provide a device of this character embodying a dial and hands moving over the dial to indicate the movements of the mechanism, for the amusement and convenience of the operators of the device.

15 A further object of the invention is to provide means for automatically controlling the operation of the pay off mechanism of the machine, whereby the number of checks, slugs or articles released by the machine, may be varied.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a side elevational view of the frame 30 in which the operating mechanism of the device is mounted.

Figure 2 is a longitudinal sectional view therethrough.

Figure 3 is a rear elevational view of the operating mechanism.

Figure 4 is a front elevational view thereof.
Figure 5 is a sectional view taken on line 5—5.

Figure 6 is a sectional view taken on line 6—6 of Figure 1.

40 of Figure 1.
Figure 7 is an enlarged rear elevational view of the operating mechanism, illustrating the means for retarding the movement of the operating mechanism when the governor of the mechanism reaches a predetermined slow speed.

Figure 8 is a sectional view taken on line 8-8 of Figure 1.

50 Referring to the drawings in detail, the device comprises a frame indicated generally by the reference character 5, the frame comprising the front plate 6 and rear plate 7, the plates 6 and 7 being held in spaced relation with respect to each other by means of the spacers 8 which are secured in position by means of the screws 9.

55 that extend through openings in the plates 6 and

7 and pass into the threaded ends of the spacers 8.

Positioned within openings formed in the plates 6 and 7, are bearings 10 and 11, the bearing 10 accommodating the shaft 12, while the bearing 11 accommodates the tubular shaft 13 through which the shaft 12 operates. 5

Secured to the plate 7, is a rearwardly extended bracket 14 that provides a support for the bearing 15 through which the shaft 16 extends, 10 the shaft 16 supporting the beveled pinion 17 at its upper end that meshes with the pinion 18 loosely mounted on the shaft 12, as clearly shown by Figure 2 of the drawings.

Mounted for movement longitudinally of the shaft 16, is a sleeve 19 to which the upper links 20 of the governor 21 are pivotally connected. A spring indicated at 22 is mounted on the shaft 16 at a point adjacent to the governor 21, and normally acts to move the inner ends of the upper links 20, upwardly, retracting the weights 23 of the governor. Mounted on the shaft 16 and disposed above the upper end of the sleeve 19, is a collar 24 which is normally urged upwardly by the action of the sleeve 19 and spring 22. A ball bearing race indicated at 25 is disposed between the upper end of the sleeve 19 and collar 24 to permit of free rotary movement of the shaft 16 within the sleeve 19 and with respect to the collar 24. Resting on the upper end of the collar 24 is a ball bearing race 26 on which the collar 27 rests, the collar 27 providing a support for the lower end of the coiled spring 28 that has its upper end connected with the arm 29 which is shown as extending laterally there-

from. The arm 29 is secured to one end of the lever 30 which is pivotally connected to the rear plate 7 of the frame, one end of the lever 30 being curved upwardly to engage the teeth 31 of the wheel 32 that is keyed to shaft 12. The opposite end of the lever 30 is formed with an opening through which one end of the coiled spring 33 extends, the opposite end of the spring 33 being secured to the rear plate 7, by means of the clip 34. Thus it will be seen that since the spring 33 is of the contractual character, the upwardly curved end of the lever will be normally held out of contact with the teeth of the wheel 32. As the sleeve 19 moves upwardly, due to the governor contracting, it will be seen that the curved end of the lever 30 will move into engagement with the teeth 31 acting as a brake, to retard movement of the shaft 12, and that when the apparatus is set in motion, the downward movement of the sleeve 19 will act to move the 55

arm 29 away from the lever 30, allowing the spring 33 to disengage the lever 30 and teeth 31, allowing the wheel 32 to rotate freely with the shaft 12. Rotary movement is imparted to the 5 shaft 12, by the pinion 18, which is provided with a clutch face 35 held in frictional contact with the wheel 32, by means of the coiled spring 36 which is tensioned by the nut 37 positioned on the threaded end of the shaft 12.

10 Keyed to the shaft 12 is the control disk 38 which is provided with notches 39 arranged in spaced relation with respect to each other and extending inwardly towards the hub of the disk, from the periphery thereof. These slots 39 are of 15 various lengths, for purposes to be hereinafter more fully described. Secured to the shaft 12, by means of the key 40, is a pinion 41 which is substantially small, the pinion 41 meshing with the large pinion 42 secured to the shaft 43 that 20 is mounted between the front and rear plates 6 and 7, as shown by Figures 1 and 2 of the drawings. The reference character 44 designates a substantially small pinion that meshes with the pinion 45 which in turn is keyed to the tubular 25 shaft 13, to rotate therewith. A control disk indicated at 46 is also keyed to the tubular shaft 13, and is also provided with slots indicated at 47 that extend inwardly from the periphery thereof, the slots of the control disk 46 being of 30 various lengths.

Mounted between the front and rear plates 6 and 7, are bearing blocks 48 and 49, the bearing block 48 being provided with an elongated opening 35 through which the blade 50 extends, the blade being of a width to extend across the space occupied by the control disks 46 and 38, so that when the slots of the disks 46 and 38 are in proper alignment, the blade may pass thereinto, in a manner as shown by Figure 2 of the drawings. 40 This blade 50 is supported at the upper end of the vertically movable bar 51 that operates through an opening formed in the bearing block 49. The lower end of the bar 51 connects with the bar 52 that in turn controls the operation of the pay 45 off mechanism, which plays no part in the present application, but which is operated by vertical movements of the bar 52.

Pivottally connected with the ear 53 that extends forwardly from the plate 6, is a lever 54 50 that has pivotal connection with the bar 51, through the pin 55 that moves in the elongated opening disposed intermediate the ends of the lever 54. The free end of the lever 54 is bifurcated and engages the pins 56 that extend laterally 55 from the collar 24. Thus it will be seen that due to this construction, the bar 51 and blade carried thereby, are moved vertically, by the action of the lever 54 and sleeve 19. Secured to the front plate 6, is a dial indicated at 57, the dial being provided with suitable indicia, preferably numbers, over which the hands 58 and 59 operate, the construction of the dial and hands simulating the face of a clock. On the extreme lower end of the shaft 16, is a pinion 60 that is in mesh with the pinion 61, the latter pinion being the power pinion, by means of which rotary movement is imparted to the shaft 16 from a suitable operating mechanism not shown.

The operation of the device is as follows: Assuming that the governor and sleeve 19 are in the 70 positions as illustrated by Figure 2 of the drawings, and the operating mechanism not shown, and which is usually in the form of a lever, is moved to rotate the pinions 60 and 61. As the pinions 60 and 61 operate, the governor is caused

to expand, drawing the sleeve 19 downwardly. As the sleeve 19 moves downwardly, the lever 54 is moved to the position as shown by Figure 1 of the drawings, with the result that the bar 51 moves downwardly causing the blade 50 to disengage the control disks 38 and 45. As the pinion 60 slows up, the governor operates to move the sleeve 19 upwardly, as the weights of the governor contract, with the result that the arm 29 moves into engagement with the teeth of the wheel 32 10 stopping the mechanism. The lever 54 is also moved to move the blade 50 into engagement with the control disks 38 and 46. As the blade moves into contact with the peripheries of the control disks 38 and 46, the bar 52 will not be 15 moved sufficiently to operate the dispensing mechanism but when the blade 50 moves into aligning slots of the disks, the operating bar 52 will be moved a distance to release articles from the machine. This distance of movement of the bar 52 is controlled by the depth of the slot into which the blade 50 extends, thereby regulating the number of articles dispensed by the machine. As the shaft 12 rotates, the hands 58 and 59 will be moved over the dial, and the people operating the device may determine at a glance, whether they have picked the lucky or pay off number. It will of course be understood that the various pinions and mechanism of the device will be set prior to the operation of the machine, so 20 that when the indicating hands move to predetermined positions, or positions that may be known as the pay off positions, the bars 51 and 52 will operate the pay off mechanism not shown. 25

Due to the fact that the pinion 18 drives the wheel 32, through the friction clutch mechanism 35, it is obvious that when the shaft is stopped, by the action of the arm 30, the sudden stopping of the mechanism will not damage the operating mechanism, since the structure as described will 30 permit of a slight slippage between the pinion 18 and wheel 32.

It might be further stated that the frame will be mounted in a suitable cabinet not shown, to 35 meet the requirements of use.

What is claimed is:

1. The combination with the operating bar of a dispensing machine, said operating bar having a blade at the upper end thereof, of a control device comprising a frame, a main horizontally disposed shaft mounted within the frame, an indicating hand secured to the forward end of the shaft to rotate therewith, a sleeve loosely mounted on the forward end of the shaft, an indicating hand secured to the outer end of the sleeve, a gear keyed to the inner end of the shaft, a gear keyed to the inner end of the sleeve, a power pinion loosely mounted on said shaft, a friction clutch connecting the power pinion with said gear, a power shaft, a pinion on one end of the power shaft and meshing with said power pinion for transmitting movement to said main shaft and hand secured thereto, through the pinions and gear, gearing adapted to transmit movement of the main shaft to the sleeve rotating the second mentioned hand, a control disk secured to said horizontal shaft and having notches of various depths extending inwardly from the peripheries thereof, and governor-controlled means including an arm movable into engagement with said pinion and adapted to stop rotation of said main shaft and sleeve, and means for moving said operating bar whereby the blade engages within said notches for regulating the movement of said operating bar simultaneously with the operation of the 50 55 60 65 70 75 80 85 90 95 100

governor-controlled means to stop rotation of said hands.

2. The combination with the operating bar of a dispensing machine, said operating bar having a blade at the outer end thereof, of a control device comprising a frame, a main horizontal shaft mounted within the frame, an indicating hand mounted on the forward end of the shaft, a gear keyed to the shaft, a power pinion loosely mounted on said shaft, a sleeve on the shaft, an indicating hand on the forward end of the sleeve, gearing adapted to transmit rotary movement to the sleeve, a friction clutch connecting the power pinion with said gear, a power shaft, a pinion on one end of the power shaft for transmitting move-

ment to said main shaft through the pinion and gear, spaced control disks secured to said shaft and sleeve respectively, and having notches of various depths extending inwardly from the peripheries thereof, said control disks having certain of their notches aligning, and governor-controlled means including an arm movable into engagement with said gear stopping the rotation of said main shaft, and means controlled by said governor-controlled means and including an arm connected with said operating bar, for moving said blade into said notches of the control disks, and the depth of said notches regulating the movements of said operating bar.
